UNITED STATES PATENT OFFICE

EUSTACE CREEES AND CHARLES S. COURT, OF PROVIDENCE, RHODE ISLAND,
ASSIGNORS TO THE WATSON AND NEWELL COMPANY, A CORPORATION
OF RHODE ISLAND.

DESIGN FOR A HANDLE FOR SPOONS OR SIMILAR ARTICLES.

SPECIFICATION forming part of Design No. 35,996, dated August 12, 1902.

Application filed June 20, 1902. Serial No. 112,555. Term of patent 7 years.

To all whom it may concern:

Be it known that we, EUSTACE CREEES and CHARLES S. COURT, citizens of the United States, residing at Providence, in the county of Providence and State of Rhode Island, have invented and produced a certain new, original, and ornamental Design for the Handle of a Spoon or Similar Article, (Case C,) of which the following is a specification, reference being had to the accompanying drawings, forming part thereof.

Figure 1 is the obverse of a spoon-handle embodying our design, and Fig. 2 the reverse of the same.

As shown in the drawings, the leading or material feature of our design consists in the following arrangement of the representation of poppy leaves and blossoms: The head of the handle contains the representation of a full-blown poppy *a*, from one side of which emerges in an upward direction a bud *b*. From the other side upwardly foliates *c*, which, with the bud *b*, converge to form the crest of the handle. Branching from one margin of the handle-stem are a series of upwardly-directed poppy-leaves *d*, some of whose extremities disappear beneath the poppy *a*. From the same margin also, about midway the length of the handle, branches a bud *e*. Below this are marginal foliates *f*. Upon the margin of the handle opposite that already

described and at irregular intervals are inwardly and upwardly directed foliates *g*. At the base of the handle is the representation of a poppy-leaf *h*.

The reverse ornamentation consists, essentially, of marginal beading *i*, from which radiate inwardly in the head of the handle foliates *j* and converge at the handle extremity. Embraced by the beading on either side of the center of the head of the handle are upwardly-directed foliates *k*, and within these interlaced stems *l*, longitudinally disposed upon the handle and terminating in the stem thereof. The lower extremities of the beading *i* terminate in foliates *m*.

It is evident that our design is applicable to the handles of a knife or similar article.

Having described our invention, what we claim as new, and desire to secure by Letters Patent, is—

The ornamental design for the handle of a spoon or similar article, as herein shown and described.

In testimony whereof we have affixed our signatures in presence of two witnesses.

EUSTACE CREEES.
CHARLES S. COURT.
